DRILL STEEL CENTRALIZER

William A. Smith, Jr., Cleveland, Ohio, assignor
to The Cleveland Rock Drill Company, Cleve-
land, Ohio, a corporation of Ohio

Application March 7, 1939, Serial No. 260,348

4 Claims. (Cl. 255—45)

This invention relates broadly to rock drills, but more particularly to a centralizer for drilling steels operated by a rock drill of the drifter type.

One object of this invention is to provide a rock drill with an efficient drill steel centralizer for maintaining the drill steel in perfect alignment with the drill when starting a drill hole.

Another object of this invention is to produce a drill steel centralizer constructed and disposed in a manner enabling it to be automatically moved into inoperative position by the drill during its feeding motion to the work, the centralizer being characterized by a simple construction which is strong, durable and efficient.

Other objects and advantages more or less ancillary to the foregoing reside in the specific construction and aggroupment of the elements peculiar to this structure, as will become apparent from a more complete examination of this specification.

In the drawing:

Fig. 1 is a side elevational view of the front end of a rock drill embodying the invention.

Fig. 2 is a top plane view looking in the direction of the arrows 2—2 in Fig. 1.

Fig. 3 is a view similar to Fig. 1 showing the centralizer in inoperative position.

Fig. 4 is a cross sectional view taken in a plane indicated by line 4—4 in Fig. 1.

Fig. 5 is a longitudinal sectional view taken in a plane indicated by line 5—5 in Fig. 4.

Fig. 6 is an end view looking in the direction of the arrows 6—6 in Fig. 3.

Referring to the drawing, 10 represents the front end of a rock drill slidably mounted on a stationary shell 11 for feeding to the work a drill steel 12 operatively mounted within the front end 10, and terminated by a cutting end or bit 13 engageable with the work. To the front end of the shell 11, there is rigidly secured by bolts 14 a support 15 extending longitudinally therefrom and having its free end formed with two laterally spaced apertured lugs 16 having a stationary horizontal bolt or pivot 17 extending therethrough transversally of the support and held in position by a nut 18. Rotatable on the pivot 17 between the lugs 16, there is the base of a T-shaped arm 19 having the ends of its cross head 20 each formed with an apertured lug 21 located rearwardly of the body of the arm. In each lug 21, there is rotatably mounted a vertical shaft or pivot 22 perpendicular to the pivot 17 and extending transversally of the support. The pivot 22 is secured against endwise movement in one direction by a nut 23 and in the

other direction by a finger 24, which finger extends laterally from the pivot 22 and is terminated by a drill steel guiding end 25 adapted to fit partway around the drill steel 12. In order to enable horizontal swinging movement of the fingers 24 without interference from the drill steel 12, the pivots 22 are located rearwardly of the drill steel guiding ends 25 relative to the cutting end 13 of the drill steel 12. The lugs 21 each carries a stop 26, the purpose of which will be explained later. In the arm 19, there is provided a spring pressed plunger 27 engageable with flats 28 and 29 formed on the stationary pivot 17 and disposed at 90° from each other, which plunger and its component spring 30 are held in operative position by a removable plug 31. Each apertured lug 21 is also provided with a spring pressed plunger 32 located within a bore 33 closed by a plug 34, which plunger is engageable with angularly disposed flats 35 and 36 formed on the pivots 22.

In the operation of the device, when the drill steel centralizer is positioned as shown in Fig. 1, the end 25 of the fingers 24 are partly surrounding the drill steel 12 as shown in Fig. 4, thereby preventing lateral movement of the drill steel when starting the drill hole. As the rock drill is fed forwardly to the work, the front end 10 will first engage the fingers 24 of the centralizer to rotate them longitudinally relative to the support into the position shown in the dotted line in Fig. 2, that is, into operative engagement of the stops 26. This swinging motion of the fingers 24 is possible without interference from the drill steel 12 due to the position of their pivots 22 rearwardly of their drill steel guiding ends 25. In this instance, the fingers' plungers 32, previously engaging the flats 35 to maintain the fingers in operative position, will now engage the flats 36 to maintain the fingers in inoperative position against accidental rotation. After the fingers are engaging the stops 26, the front end 10 acting on the fingers will cause the swinging movement of the arm 19 in a clockwise direction in Fig. 1, or longitudinally relative to the support, to shift the centralizer into inoperative position as shown in Fig. 3. During this swinging movement of the arm 19, the spring pressed plunger 27 will pass over the junction of the flats 28 and 29 formed on the stationary pivot 17 and finally engage the flat 29 to maintain the centralizer in inoperative position. The centralizer being now located out of the path of the rock drill, will enable further drilling operation or

feeding movement of the rock drill without interference.

When the rock drill has been moved back preparatory to the drilling of another hole, the arm 19 of the centralizer may manually be shifted from the position shown in Fig. 3 to the position in Fig. 1 and be held in that position by the engagement of the spring pressed plunger 27 with the flat 28. Subsequently each finger 24 may also be manually shifted into operative position relative to the drill steel 12 and be held in that position against accidental rotation by the spring pressed plungers 32 engaging the flat 35.

From the foregoing description, it will be understood that the centralizer when in operative position, as shown in Fig. 1 is automatically shifted into the inoperative position shown in Fig. 3 due to the feeding motion of the rock drill relative to the shell 11, thus enabling the drilling operation to take place without interference from the centralizer.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

I claim:

1. In a drilling apparatus, the combination with a supporting shell having a drill slidable thereon and a drill steel extending longitudinally from the drill, of a drill steel centralizer mounted on the forward end of the shell including an arm pivotally connected to said shell for rotation lengthwise of the shell, a pair of drill steel guiding fingers carried by said arm for rotation therewith, and a pivotal connection between said arm and each finger enabling independent rotation of said finger relative to said arm toward or away from said drill steel within a plane passing through the longitudinal center axis of said drill steel.

2. In a drilling apparatus, the combination with a supporting shell having a drill slidable thereon and a drill steel extending longitudinally from the drill, of a drill steel centralizer mounted on the forward end of the shell including an arm pivotally connected to said shell for longitudinal rotation relative thereto, a pair of parallel pivots in said arm one on each side of the drill steel, and a drill steel guiding finger on each pivot independently rotatable relative to said arm toward or away from said drill steel within a plane passing through the longitudinal center axis of said drill steel.

3. In a drilling apparatus, the combination with a supporting shell having a drill slidable thereon and a drill steel extending longitudinally from the drill, of a drill steel centralizer mounted on the forward end of the shell including a T-shaped arm carried by the shell, a pivotal connection between said shell and arm affording pivotal movement of the arm lengthwise of the shell, a pair of drill steel guide fingers carried by said arm, and a pivot in said arm for each finger enabling independent pivotal movement of said fingers toward or away from said drill steel within a plane passing through the longitudinal center axis thereof.

4. In a drilling apparatus, the combination with a supporting shell having a drill slidable thereon and a drill steel extending longitudinally from the drill, of a drill steel centralizer mounted on the end of the shell including an arm pivotally carried by the shell for swinging movement longitudinally of the shell, a pair of laterally spaced pivots journaled in said arm, and a drill steel guide finger carried by each pivot independently movable toward or away from said drill steel within a plane passing through the longitudinal center axis thereof, said fingers extending at right angles from said pivots and ahead of the pivots relative to the direction of movement of said fingers away from said drill steel.

WILLIAM A. SMITH, JR.
